(57) **CLAIM**

The ornamental design for low end appliance server bezel, as shown and described.

DESCRIPTION

FIG. 1 is a front elevational view of a low end appliance server bezel showing our new design;

FIG. 2 is a right-side elevational view thereof;

FIG. 3 is a left-side elevational view thereof;

FIG. 4 is a top plan view thereof; and,

FIG. 5 is a bottom plan view thereof.

The broken line showing the rear cabinet in FIG. 2 is for illustrative purposes only and forms no part of the claimed design.
